DESIGN FOR A VIGIL CANDLE TUMBLER OR SIMILAR ARTICLE

Henry Rithner, Wellsburg, W. Va.

Application April 21, 1939, Serial No. 84,459

Term of patent 14 years

To all whom it may concern:

Be it known that I, Henry Rithner, a citizen of the United States of America and resident of Wellsburg, county of Brooke, and State of West Virginia, have invented a new, original, and ornamental Design for a Vigil Candle Tumbler or Similar Article, of which the following is a specification, reference being had to the accompanying drawing, forming part thereof, in which—

Figure 1 is a side elevational view of a vigil candle tumbler or similar article, showing my new design; and

The characterizing features of the design comprise a vigil candle tumbler of the configuration shown, having the outer surface thereof decorated with hemi-spherical nodules having the configurations and arranged in the specific manner shown.

I claim:

The ornamental design for a vigil candle tumbler or similar article, substantially as shown and described.

HENRY RITHNER.
